UNITED STATES PATENT OFFICE

CHARLES SPONSEL, OF MANCOS, COLORADO

HYPODERMIC KIT

Application filed December 17, 1928. Serial No. 326,541.

This invention relates to a kit containing a hypodermic syringe, a serum bottle, a container for disinfectants and a container for disinfectant solutions. This group forms a 5 convenient little package that may be carried in a small space, or even in the vest pocket, for use on ranches for the treatment of infected cattle, or as a preventive measure.

The purpose of the syringe is to carry just 10 enough for one treatment and is to be filled after each treatment; the disinfectants are for the purpose of properly disinfecting the tube or needle of the syringe. The serum bottle contains the serum to be used in the 15 treatment of the cattle.

While this package is particularly designed for use on ranches in the treatment of cattle, a similar package might be used for treatment of human beings, with necessary 20 modifications as to the contents of the package.

There is shown in the accompanying drawings a preferred embodiment of this invention.

25 Referring to the drawings:

Figure 1 is a front view of the package with the lid open, showing the contents in dotted lines.

Figure 2 is a top plan view of the package 30 with the lid folded back.

Figure 3 is similar to Figure 2, with the contents removed.

Figure 4 is a cross section on the line 4—4 of Figure 2.

Figure 5 is a section on the line 5—5 of 35 Figure 2.

The numeral 1 indicates a container, which may be made of sheet metal, tin or even paper, the only requisite being that it should 40 be rigid and have enough body to support the contents. This package is more or less rectangular in shape, having a lid adjacent to the top to form a closure therefor. The front part of the upper part of the body of the package is cut away so as to provide space 45 for ready access to the contents of the case or package.

The cut away part of the package is indicated by the numeral 2, and the corresponding 50 extended part of the lid is indicated by

the numeral 3, and the point of connection between the lid and the body part, which has a hinge, is indicated by the numeral 4.

For the purpose of making the corners smooth and easy to fit within the pocket they 55 are rounded as indicated by the numeral 5.

For the purpose of locking the closure or lid to the box member there is provided on the lid a suitable opening 6, which engages a corresponding projection 7 on the front 60 part of the box to hold the lid in engagement with the box to close the contents within the box. All that is necessary to do to open the package is to press upon the container, just below the lock, and the snaps will become 65 released.

This little package or container is divided essentially into three compartments. This division is effected by a single piece of material, the same as that of which the body of 70 the container is composed. The main part of the partition that separates the container into compartments is indicated by the numeral 8, and is arranged vertically and cross-wise of the box from the lefthand side to substantially the center of the box, a little forward of the center from the back to the front. This partition does not extend to the bottom of the box; neither does it extend to the top, as is clearly indicated in Figure 1.

At the point where the partition 8 ends the partition piece is bent back to form a second partition 9. This partition separates the compartment that contains the serum from the compartment that contains 85 the disinfectant solution. The partition 8 separates the container for the disinfectant solution from the container for the disinfectant and the hypodermic needle.

Extending from the point where the partition 9 branches off from the partition 8 is a 90 forwardly projecting part of the partition 10. This part of the partition is circular and partakes of the shape of the container in that 95 part of the package. The partition extends about one-half of the depth of the package; for about one-fourth the depth of the container there is no partition; then for about two-fourths there is a partition; then for the other one-fourth up to the top there is no 100

partition. By this means there is formed a structure having three compartments, one in which there is the serum bottle; another in which there is the disinfectant solution and another in which there is the disinfectant and the hypodermic syringe.

The hypodermic syringe is shown in Figures 2 and 4 in position in the package. The needle part of the hypodermic syringe is placed and fits in a slit in a false bottom 11. The hole in which this needle part of the hypodermic syringe fits is indicated by the numeral 12. This false bottom is attached near the lower edge of the partitions and is horizontal with the bottom of the case, or container.

The needle part of the hypodermic syringe is indicated by the numeral 13, while the handle part is indicated by the numeral 14. The handle part protects a bulb member 15. This bulb is of rubber and may be compressed and expanded for the purpose of receiving the serum into the needle and ejecting the serum therefrom. The purpose of the needle is to open the skin of the animal for the reception of the serum in the treatment. The serum bottle is indicated by the numeral 16, while the container for the disinfectant is indicated by the numeral 17, and the container for the disinfectant solution is indicated by the numeral 18.

It is very obvious that applicant has provided a simple and convenient device of this kind.

I desire to comprehend within my invention such modifications as may be clearly embraced within my claims and the scope of my invention.

Having thus fully described my invention, what I claim is new and desire to secure by Letters Patent, is:

1. In a medical case having a bottom, a one-piece partition in said case cooperating with the walls of said case to form a plurality of compartments, one in one end and two in the other end of the case, and a second bottom in one of said compartments integral with the partition to support a hypodermic syringe.

2. In a medical case having a bottom, a container having a greater depth at the back than at the front, a one piece partition in said container dividing it into compartments, each compartment adapted to hold a certain drug, and one compartment having a second bottom integral with the partition to adapt it to hold also a hypodermic syringe, and means to close the container.

In testimony whereof, I affix my signature.

CHARLES SPONSEL.
